(57) **CLAIM**

The ornamental design for a razor cartridge cap, as shown and described.

DESCRIPTION

FIG. 1 is a front perspective view of the razor cartridge cap of the present invention.

FIG. 2 is a rear perspective view of the razor cartridge cap of the present invention.

FIG. 3 is a bottom plan view of the razor cartridge cap of FIG. 1.

FIG. 4 is a top plan view of the razor cartridge cap of FIG. 1.

FIG. 5 is a right side elevation of the razor cartridge cap of FIG. 1.

FIG. 6 is a left side elevation of the razor cartridge cap of FIG. 1.

FIG. 7 is a front elevation of the razor cartridge cap of FIG. 1; and,

FIG. 8 is a rear elevation of the razor cartridge cap of FIG. 1.

The broken lines illustrate portions of the razor cartridge cap and form no part of the claimed design.
